UNITED STATES PATENT OFFICE.

LUDWIG BRUCKMANN, OF PFORZHEIM, GERMANY.

POCKET LIGHTER.

Application filed July 9, 1927, Serial No. 204,627, and in Germany April 13, 1927.

This invention relates to a benzine pocket-lighter with friction-wheel. The pocket-lighter presents the advantage that, to rotate the friction-wheel, it is not necessary to touch the friction wheel but merely to push a knob for producing sparks.

Benzine-pocket-lighters have become known, in which the wick is covered by a hood, carried by a two-armed lever, which is oscillated at the same time as the friction-wheel is rotated. If the free end of the two-armed lever is depressed, the wick-hood mounted on the other end of the lever is lifted off the wick, the friction wheel rotates over a cerium-rod and sparks are thrown towards the wick. The oscillation carried out by the two-armed lever amounts to about 90°. The free end of the lever is downwardly pressed by the finger, this presenting the following inconvenience. The finger loses its hold as soon as the corresponding lever-end is downwardly inclined and slips off so that the last portion of the rotation of the friction-wheel is not carried through with the impulse required for the production of sparks. A pocket-lighter of this kind is not a one-hand pocket lighter, i. e. a pocket-lighter to be operated with one hand as, if the user grips the pocket-lighter so that the bottom-plate of the same rests on the index and middle finger of the hand, the thumb depressing the lever-end, the pocket-lighter would drop from the hand at the moment when the inclination of the lever-end begins. He therefore must use the other hand for holding the pocket-lighter during the depressing of the lever-end so that he cannot use his other hand for holding the cigarette or cigar to be lighted.

This inconvenience is absolutely avoided by the present invention, which consists in using for the depressing of the lever-end a knob mounted on a shaft, adapted to be shifted in longitudinal direction in the body of the pocket-lighter in opposition to the action of the spring, said knob-pressing at the downward movement against the nose of the friction-wheel, so that the wick-hood is lifted off the wick and the friction-wheel rotated at the same time.

The knob on the shaft is not inclined but shifted only in the longitudinal direction of the finger-pressure. The finger can therefore not slip off and it can be used at the same time for holding the pocket-lighter. It is therefore possible to manipulate the pocket-

lighter with one hand, the bottom plate of the pocket-lighter resting on the index and middle finger and the thumb of the same hand pressing down the knob. Dropping of the pocket lighter from the hand is absolutely avoided so that the second hand is available for any other manipulation.

An embodiment of the invention is shown, by way of example, in the accompanying drawing in which:

Fig. 1 shows the improved pocket-lighter in side elevation and in closed position.

Fig. 2 is a longitudinal section and

Fig. 3 is a top plan view of Fig. 2.

The casing 1 is closed at the bottom by a plate 2 and at the top by a plate 3.

Two tubes 4 and 5 are fixed in the plates 2 and 3 the tube 4 serving to guide a cerium-rod 6 and tube 5 serving to guide the hollow shaft 7 of the push-knob 16. The casing 1 has on the top plate 3 an extension 10 with holes 9 in its wall and serving as wind-screen, said extension being normally closed by a lid 12, oscillatably mounted on an axle 11. On this axle 11 a friction-wheel 15 having two noses 13 and 14 is rotatably mounted.

When the lid 12 is closed, the nose 13 of the friction-wheel 15 extends adjacent to the lower side of knob 16 the nose 14 bearing on the inner surface of the lid 12. When the knob 16 is depressed, in opposition to the action of a spring 17, the friction-wheel 15 rotates about 90° in the direction of the arrow-line A (Fig. 2). The sparks which are thus produced, ignite the benzine in the free end of a wick 18. At the same time as the friction-wheel 15 is rotated, the lid 12 is oscillated so that the flame projects from the wind-screen 10 which is now open at the top end.

On the inner end of the lid 12 a hood 19 for the wick is fixed and a snap-spring 20 is arranged which serves to securely hold the lid 12 in the closing position, as said spring 20 is clamped between the inner surfaces of two opposite side walls of the wind-screen 10. By this locking of the lid 12 the spark-production is favored as, after the jamming has been overcome by the pressure exerted upon the knob 16, the friction-wheel 15 will rapidly rotate over the end of the cerium rod 6 under the influence of the knob 16 which is depressed without considerable resistance.

When the cerium-rod 6 is no longer strongly pressed against the friction-wheel 15 it might happen that the lid 12 opens ac-

identally in the pocket so that, as the wick-hood 19 is no longer tightly pressed on the top-plate 3 of the body of the pocket-lighter benzine can evaporate. This must however be prevented in any position of the pocket-lighter. For this purpose serves the spring 20 which securely holds the lid 12 in closed position, owing to the friction on the inner side of wall 25. A further advantage is that for opening the lid the resistance of spring 20 has to be overcome by a pressure on the push-knob 16. To open the lid a strong pressure has to be exerted on the knob 16. If after the lid has been slightly lifted the frictional resistance of the spring 20 ceases, as it has come out of contact with the wind-screen, the friction wheel 15 will be rapidly rotated by the strong pressure on the push knob 16 so that a strong jet of sparks is produced, this being necessary for the ignition of the benzine-gases coming from the wick 18.

The spare cerium-rods 22 are stored in the hollow shaft 7 of knob 16. The knob 16 is removably fixed in the upper end of shaft 7 by means of elastic arms 24 so that it closes the top end of the magazine.

In order to prevent excessive heating of the wind-screen 10 an inner wall 25 having air holes (Fig. 3) may be arranged at a short distance from the outer wall of the wind-screen.

The casing may be of any desired shape, size, material and ornamented or not.

I claim:—

35 1. A benzine pocket-lighter, comprising

in combination with a casing, a cerium-rod, a friction-wheel rotatably mounted above the top end of said cerium-rod, a nose on said friction-wheel, and a spring-controlled push knob mounted on a shaft shiftably guided in 40 said casing so that the edge of said knob standing above said nose of said friction-wheel makes said friction-wheel rotate when said knob is being depressed so that sparks are produced.

2. A benzine-pocket-lighter as specified in claim 1, comprising in combination with the casing the push-knob the friction-wheel and the cerium-rod, a wind-screen on the top plate of said casing, a horizontal axle journaled in 50 said wind-screen and carrying said friction-wheel, a lid for said wind screen and fixed on said horizontal axle, a wick in said casing the upper end of said wick projecting into said wind-screen, a wick-hood on the 55 inner surface of said lid, and a blade-spring on the inner surface of said lid for securely holding said lid in the closing position.

3. A benzine pocket lighter as specified in claim 1, comprising in combination with a 60 push knob, a hollow shaft of said push knob serving as magazine for spare cerium rods, and elastic downwardly directed arms fixed on the lower surface of said push-knob and designed to hold said knob in said hollow 65 shaft and serving as cover for said hollow shaft.

In testimony whereof I affix my signature.

LUDWIG BRUCKMANN.
